UNITED STATES PATENT OFFICE

MILTON E. WALKER, OF CHICAGO, ILLINOIS

CANNING MACHINE

Application filed December 31, 1930. Serial No. 505,938.

This invention relates broadly to certain new and useful improvements in canning machines, and the primary object of the invention is to provide a machine of this type, especially adapted for canning prepared spaghetti.

A still further object of the invention is to provide a machine which will permit of filling cans with prepared spaghetti in a practical and efficient manner without unnecessary loss of time and with a minimum of labor.

A still further object of the invention is to provide a machine for filling cans with prepared spaghetti that consists of but relatively few parts, requires but little skill to operate, will insure the proper proportionment of the spaghetti to each can, and further, a machine of this character which will be inexpensive in maintenance.

Other objects and advantages of the invention will become apparent during a study of the following description, taken in connection with the accompanying drawings

25 wherein:

Figure 1 is a top plan view of the machine.

Figure 2 is a side elevational view thereof, the endless conveyor being shown in section.

Figure 3 is a vertical sectional elevational view taken substantially on the line 3-3 of Figure 1.

Figure 4 is a top plan view of the movable measuring and filling block.

Figure 5 is a vertical sectional view taken 35 substantially on the line 5-5 of Figure 3.

Figure 6 is a side elevational view of the endless conveyor.

Figure 7 is a transverse sectional view taken substantially on line 7-7 of Figure 1.

40 Figure 8 is a vertical sectional elevational view taken substantially on the line 8-8 of Figure 9.

Figure 9 is a vertical sectional view taken substantially on the line 9-9 of Figure 2.

45 Figure 10 is a somewhat diagrammatic and

elevational view of the means for imparting transmittent movement to the endless conveyor.

Figure 11 is a detail sectional view taken substantially on the line 11-11 of Figure 10.

50 Figure 12 is a fragmentary plan view showing certain arrangements of shaft as embodied in the present invention.

Figure 13 is a face view of a disk provided with an eccentric groove comprehended by 55 the present invention.

Figure 14 is a sectional elevational view of a ratchet showing the adjustment means therefor.

Figure 15 is a detail sectional elevational view taken substantially on the line 15-15 of Figure 2.

With reference more in detail to the drawings it will be seen that 1 designates a suitable leg supported table that has rising from adjacent the forward end thereof a frame structure that includes supports 2 and 3, which vertical supports 2 and 3 support on their upper ends an inclined tray 4 for receiving spaghetti or the like commodity to 70 be canned.

Adjacent one end thereof, the tray 4 is contracted and merges into an integral substantially horizontally disposed discharge trough 5 that has a feed spout 6 leading downwardly 75 therefrom.

A guide platform 7 is supported on a transverse member 8 connecting opposed vertical frame members 2, and a cross member 9 connecting the upper ends of relatively short 80 vertical frame members 10.

Slidably arranged on platform 7 is what may be termed a combined feed and measuring box designated generally by the reference character B. The combined feed and 85 measuring box B includes a lower section 11 that is hollowed out as at 12 to reduce the weight of the section. Adjacent one end thereof the section 11 is provided with a vertical hole or opening 13. The combined meas- 90

uring and feed box B also includes an upper inverted U-shaped section 14 which has the ends 15 thereof serrated or otherwise formed to provide teeth for engagement with complementary teeth provided on the ends of the section 11 whereby the sections 11 and 14 may be adjusted relative to one another and maintained in said adjusted position through the medium of locking screws 16 that are passed through the ends 15 and engage the corresponding ends of the section 11.

Thus section 14 may be raised or lowered and maintained in a raised or lowered position relative to section 11. Section 14 is provided with an opening adapted to register with the opening 13 of section 11, and depending from the section 14 about its opening is a cylindrical extension 17 that has its lower end slidably received in the opening 13.

The spout 6 leading from the opening in the trough 5 includes two telescoping sections one of which is fixed, and the other of which 6' is longitudinally movable as may be required according to the particular adjustment of sections 11 and 14.

From the foregoing it will be apparent, that when the tubular extension 17 of section 14 is in alinement with spout 6, the spaghetti or like commodity may be forced through the spout into the tubular extension 17 and opening 13. The amount of the commodity that is received in the extension 17 and opening 13 will be such as will be necessary for filling a can of a particular size.

The aforementioned combined feed and measuring box is slidable on the platform 7 between the sides 18 of the platform. Said sides 18 are provided with internal longitudinal grooves or channels 19 for receiving the ribs 20 that project laterally from the section 11 thus providing suitable guide means for the box B during sliding movement of the latter.

At one end thereof, platform 7 projects beyond the corresponding end of table 1, and at said one end is provided with a vertical discharge spout 21.

When the box B is thus moved forwardly from its position shown in Figure 3 so as to register opening 13 with spout 21, the spaghetti or other commodity will by gravity pass from the extension 17 and opening 13 through the spout 21 into a can C. Of course, when the box B has been so moved in said forward direction, it will be apparent that the upper section 14 of the box will act as a closure for the spout thus preventing passage of the spaghetti or the commodity through the spout until tubular extension 17 is again brought into registry with the spout upon return movement of box B.

The mechanism for reciprocating box B includes a gear casing 22 that has suitably journaled in the lower end thereof a shaft 23 driven from a suitable electric motor M

through the medium of suitable belt and pulley drive means 23.

A shaft 24 has one end thereof journalled in the gear casing 22 adjacent the upper end of the gear casing, and movement of shaft 22 is transmitted to shaft 24 through the medium of suitable transmission gearing designated generally by the reference character 25 arranged within the gear casing. (See Figures 8 and 9.) Shaft 24 has its other end suitably journalled in a bearing bracket 26 rising from the table 1 adjacent one longitudinal edge of the table.

Splined to shaft 24 for rotation therewith is a cam disk 27. Disk 27 on one face thereof is provided with an eccentric groove 28 within which operates a roller 29 suitably journalled on one end on a pitman rod 30. Pitman rod 30 at its other end is pivoted between a pair of spaced parallel ears provided on one end of section 14 of box B. Said end of pitman 30 is pivoted between said ears as at 31.

A rock shaft 32 is journalled between a pair of bearings 33 mounted on table 1. Rock shaft 32 is provided with a rocker arm 34 and the free end of the rocker arm is pivotally connected with that end of pitman rod 30 which carries roller 29.

A single bolt 35 may be used for pivotally connecting the said end of pitman 30 to rocker arm 34 and for supporting roller 29.

Thus it will be seen, that when the circuit to the electric motor M is closed, movement will be transmitted from shaft 22 to shaft 24 through the transmission gearing above referred to, thus rotating cam disk 27 imparting oscillatory movement to pitman 30 for effecting a sliding or reciprocatory movement of the combined feed and measuring box B. Of course, movement of box B will be so timed as to permit the same to remain in its retracted position, or in that position shown in Figures 2 and 3, for a sufficient period of time as may be required for filling the box with the necessary quantity of spaghetti. When the box has been moved forwardly through the mechanism just described, so as to position the opening 13 over the spout 21, cam disk 27 will have rotated a sufficient fraction of its revolution as to cause roller 29 to be working in that portion of groove 28 designated generally by the reference character 28'. The walls of the groove at that portion 28' of the groove are suitably machined as to provide alternating recesses and projections as will cause a jerking motion being imparted to pitman 30, consequently shaking or vibrating box B for agitating and insuring a thorough discharge

of the commodity through the spout 21 into a can C disposed beneath the spout for receiving the spaghetti or commodity.

For feeding cans successively and intermittently to the spout 21 there is provided an

endless conveyor that extends transversely with respect to the table 1 at the forward end of the table and which is movable beneath the extended end of platform 7.

The conveyor comprises a suitable frame structure designated generally by the reference character F and in the end thereof are journalled sprockets 36 over which sprockets are trained the endless chains 37 of the endless conveyor designated generally by the reference character 38. Of course, any desired type of endless conveyor may be used, and the conveyor has the runs thereof equipped with spaced apart lugs 39 for engaging the cans C for moving the cans successively into alignment with the discharge spout 21.

The cans are maintained in alignment on the conveyor between a pair of spaced parallel guide bars 40 that extend longitudinally of the conveyor and are supported above the upper run of the conveyor through the medium of suitable brackets 41 engaged with the guides 40 and adjustably engaged with the sides of the frame F as at 42. Thus the guides 42 may be maintained in spaced parallelism for accommodating therebetween the cans C, the guides 40 being spaced any desired distance apart as may be needed for accommodating the particular sized can on the conveyor.

To operate the conveyor intermittently, and synchronously with the feed box B there is provided, a horizontally disposed shaft 43 journalled in brackets 44 mounted on one side edge of table 1.

Shafts 24 and 43 are operatively connected together through the medium of a vertical shaft 46 journalled in suitable bearings also on said one side of table 1. Shafts 46 and 24 are operatively connected through the medium of suitable gearing 45, and shaft 46 and shaft 43 are operatively connected together through the medium of suitable gearing 47.

That end of shaft 43, adjacent the conveyor, has suitably splined thereto a disk 48 provided with a radial slot 49 for receiving therein one end of a pivot and eccentric pin 50. The eccentric pin 50 may be disposed at any predetermined point of adjustment within slot 49 through the medium of a collar integral with the pin, and a nut 51 threadedly engaging one end of the pin 50 and cooperating with the collar for the purpose apparent. Pivottally engaged with the free end of the eccentric pin 50 is a link 52, which link 52 adjacent its free end is pivotally connected to the lower end of an arm 53. Arm 53 intermediate its ends is rockably mounted on one end of shaft 54 to which is keyed one of the sprockets 36. Keyed to the shaft 54 adjacent its outer end, is a disk 55 which has mounted thereon a ratchet wheel 56. Ratchet wheel 56 may be adjusted rela-

tive to the disk 55 through the medium of suitable bolt and slot means 57. Manifestly, adjustment of ratchet wheel 56 relative to disk 55 will be necessary according to the capacity of the can to be carried by the endless conveyor.

To the free end of arm 53 is pivotally mounted a dog 58 that is normally engaged with the teeth of the ratchet wheel 56 through suitable spring means 59.

From the foregoing then it will be seen that as shaft 24 rotates for actuating the box B in a manner before explained in detail, movement of shaft 24 will be transmitted to shaft 43 thus rotating disk 48 resulting in an oscillatory movement being imparted to link 52 for rocking arm 53. As arm 53 is rocked, dog 49 will successively engage the teeth of the ratchet wheel 56 thus imparting a step by step or intermittent movement of the conveyor so that as one can is filled, and moved from adjacent spout 21, a second can will be moved into alignment with the spout in timed relation with the movement of box B, so that when box B is moved forwardly whereby its opening 13 is moved into registry with spout 21 an empty can on the conveyor will also be in registry with the spout for receiving the contents of the box B.

Even though I have herein shown and described the preferred embodiment of the invention, it is to be understood that the same is susceptible of various changes, modifications and improvements coming within the scope of the appended claims and the spirit of the invention as herein described.

Having thus described my invention, what I claim as new is:

1. A filling machine including an inclined tray terminating in a trough having a longitudinally extensible discharge spout, a platform mounted below the tray, a member slideable on the platform adapted to receive the commodity dispensed from said spout, said platform remote from the terminus of said spout being provided with a discharge opening, a conveyor movable beneath said platform and adapted to support the receptacles thereon for successively alining the receptacles with said discharge opening, and means for actuating said slideable member and conveyor in timed relation with respect to one another, said last mentioned means including means for imparting reciprocatory movement to said slideable member, and intermittent movement to said conveyor.

2. A filling machine including an inclined tray terminating in a trough having a longitudinally extensible discharge spout, a platform mounted below the tray, a vertically adjustable member slideable on the platform adapted to receive the commodity dispensed from said spout, said platform remote from the terminus of said spout being provided with a discharge opening, a conveyor mov-

able beneath said platform and adapted to support receptacles thereon for successively alining the receptacles with said discharge opening, means for actuating said slidable member and conveyor in timed relation with 5 respect to one another, said last mentioned means including means for imparting reciprocatory movement to said slidable member, and intermittent movement to said conveyor, together with means for imparting a vibratory movement to said slidable member when the latter is at the limit of its sliding movement in one direction.

3. A filling machine including in combination a tray adapted to receive a commodity, 15 an endless conveyor adapted to support thereon a plurality of receptacles in predetermined spaced relation, a slidably mounted member of variable capacity adapted to receive a predetermined portion of the commodity from the tray at predetermined intervals for successively filling the receptacles on said conveyor, mechanism for actuating said member and said conveyor, said mechanism including means for imparting intermittent movement to the conveyor and reciprocatory movement to said member and in timed relation whereby when said member is at the end of its movement in one direction, 25 a can on said conveyor will be in its predetermined position for receiving the commodity from said member, said mechanism further including means for imparting a vibratory movement to said member when the latter is at the end of its movement in said one direction for insuring a discharge of the commodity from said member into the receptacle.

4. A filling machine comprising a tray 40 having a vertical discharge spout, a member mounted for reciprocatory movement beneath said tray and provided with a vertical bore adapted to aline with said discharge spout for receiving a portion of the commodity on said tray, a conveyor remote from the tray and adapted to support thereon a plurality of cans arranged in predetermined spaced relation, means for actuating said member and said conveyor in timed relation 45 with one another for successively filling the cans on the conveyor from said member, means for varying the capacity of said member, and said discharge spout being longitudinally extensible to compensate for the varied capacity of said member.

5. A filling machine including in combination an endless conveyor adapted to support thereon a plurality of cans in predetermined spaced relation, a member movable transversely to the conveyor and adapted to contain a commodity of an amount equal to the amount of the capacity of one can, means for actuating said member and said conveyor for reciprocating said member and imparting 60 step by step movement to said conveyor in

timed relation whereby when said member is at the limit of its movement in one direction, said conveyor will have moved a sufficient distance for positioning a can thereon opposite to said member for receiving the contents of said member, and means for imparting a series of jerking movements to said member when the latter is in the last referred to position whereby to effect a discharge of the contents of said member into the particular can.

6. A can filling machine including in combination an endless conveyor, a reciprocating member having a discharge aperture located above said conveyor and movable transversely relative thereto, means for reciprocating said member and including means for imparting a series of relatively short strokes to said member when the discharge opening of the latter is disposed in substantial vertical alinement with said conveyor.

7. A can filling machine including in combination a travelling can holder, a tray above and laterally disposed with respect to the holder, and means movable between said tray and said holder adapted to deliver material to the cans on said holder and including a reciprocating member and means for reciprocating the same and intermittently vibrating said member.

In testimony whereof I affix my signature. 95
MILTON E. WALKER.
